UNITED STATES PATENT OFFICE.

THOMAS B. DOOLITTLE, OF BRIDGEPORT, CONNECTICUT.

TELEPHONE-EXCHANGE APPARATUS.

SPECIFICATION forming part of Letters Patent No. 298,559, dated May 13, 1884.

Application filed September 16, 1881. (No model.) Patented in England February 11, 1882, No. 661.

To all whom it may concern:

Be it known that I, THOMAS B. DOOLITTLE, a citizen of the United States, and a resident of Bridgeport, in the county of Fairfield and 5 State of Connecticut, have invented certain new and useful Improvements in Telephone-Exchange Systems and Apparatus, of which the following is a specification.

My invention relates to that system of telephonic intercommunication for private and business purposes which consists of a number of telephonic lines assembled together, and so organized that each individual line establishes a direct means of communication between one 15 or more subscribers and a central or connecting office. By means of such an organization, each subscriber or other authorized person provided with a telephone or other equivalent instrument may at any time, through the intervention of the central office with which he is immediately connected, be placed in direct communication with any other subscriber who is connected in like manner with such central office, which is technically termed, an "exchange-office." In the application of such a 20 system to large towns and cities there must necessarily be great numbers of individual subscribers provided with telephonic instruments. The place where these subscribers are situated 25 will hereinafter be designated as "sub-stations," each of which must be capable of being placed in direct communication with any other at short notice whenever required. Under these conditions, however, experience has 30 shown that the assembling together of so many independent lines at one place and the greater frequency of calls for connection between different subscribers, which increase in much 35 greater proportion than the increase in the number of subscribers of sub-stations, gives 40 rise to serious difficulties and delays in performing the service of making the connections, and thus greatly diminish the economy, efficiency, and general utility of the system.

45 The object of my invention is to diminish the hereinbefore mentioned inconveniences by distributing the lines converging to a central station into different groups, each group containing such a number of lines as experience shows may be conveniently attended by a single operator, so that each such group of 50 lines constitutes in effect an independent cen-

tral station, being provided with its own special switch-board and apparatus for transmitting and receiving signals and making connections. The different switch-boards belonging to different groups of wires are connected together by direct wires, which are technically termed "trunk-wires." Secondary or auxiliary central stations or exchanges may in like 55 manner be located at different points within the geographical district embraced in the operations of the general system, and these should by preference be situated in the neighborhood of those centers of different branches 60 of business which are usually found in all large commercial cities. Each of these auxiliary central stations will serve a group of subscribers located in that particular geographical sub-district whose private or individual lines will 65 terminate therein. These auxiliary exchanges are each provided with a switch-board, and are connected with each other and with the principal central station by trunk-lines arranged 70 upon the same principle as hereinbefore described. 75

My invention comprises certain improvements in construction of switch-boards, switches, and apparatus for establishing the connection between different lines, so that the same 80 may be effected with the utmost convenience and celerity.

In the accompanying drawings, Figure 1 is a perspective view of a switch-board and operator's table embodying my improvements. 85 Fig. 2 is a side elevation, partly in section, of the signaling and connecting apparatus of one of the compartments of the switch. Fig. 2^A is a detached view of a portion of the same. Fig. 3 is a front and Fig. 4 is a rear elevation of 90 the same. Fig. 5 is a diagram illustrating the arrangement of the electrical connections in the switch-boards. Fig. 6 is a diagram illustrating the connections between different switch-boards in the same and in different offices, and Fig. 7 is a diagram of connections. 95

The switch-board represented in Fig. 1 is designed to be located at a central station and to accommodate a maximum number of fifty subscribers' or sub-station lines, which is usually found to be as great a number as can be conveniently attended by a single operator. The switch-board consists, preferably, of an upright case, A, the upper portion of which is 100

divided into boxes or compartments B B. In the drawings I have shown seventy-five of these compartments, arranged in three rows of twenty-five each, one above the other, the 5 upper one being reserved especially for trunk and connecting lines. Each compartment may conveniently be about three and a half inches in height and one inch in breadth, and about four inches in depth from front to rear. Each 50 one of these compartments is appropriated to a particular line, either a sub-station line or a trunk-line extending from another switch-board, as the case may be, and it contains all the special apparatus pertaining to that particular line.

C is the operator's table, which may be attached to the case A, containing the switch-board, and project horizontally in front of it, as represented in Fig. 1, which is the arrangement I prefer; or it may, if desired, consist of a detached table. Upon this table are mounted the connecting devices for establishing communication between one line and another, and also the general apparatus for speaking and 55 signaling, which is designed for the use of the operator or attendant in conversing with the subscribers and in making connections.

The special apparatus belonging to each individual line consists of a visual signal or annunciator for receiving signals, a key for transmitting signals, and a spring-jack or device whereby the connections with other lines are formed. I will now describe these special devices in detail, it being understood that the 55 apparatus in each compartment of the switch-board is precisely similar to that in every other one.

The several parts of the apparatus are attached to a metallic frame, which, for the sake 50 of economy and convenience, I prefer to form of a single casting, consisting of a vertical face-plate, a, (see Figs. 2, 3, and 4,) having horizontal rearward extensions, a' a'', from the latter of which extends vertically an angular bracket, a'''.

D is an electro-magnet, which is mounted upon the upper rearward extension of the frame a'', and which has an armature, d, pivoted at d', and provided with a counter-balance, d'', of a weight just sufficient to overbalance the armature d and raise the same from the poles of the electro-magnet D when no electric current is traversing the latter.

E is an annunciator-drop or visual signal, 5 which I prefer to construct in the manner illustrated in Figs. 2 and 3, it being pivoted by its lower edge at the point e, which point, being in the rear of its center of gravity, gives the drop a tendency to fall forward through 50 an angle of about forty-five degrees until stopped by the coming in contact of its bevelled lower edge, e', with the face of the plate e. The drop E is normally held in this position of unstable equilibrium by means of a 55 detent, e'', which is affixed thereto, and projects rearwardly through a slot in the face-plate, so as to take hold of the edge of the slot

d'' in the armature d. Thus it will be understood that when an electric current traverses the electro-magnet D the armature d is attracted, and, being drawn down toward the poles of the electro-magnet, is disengaged from the detent e'', which action permits the drop E to fall forward, as hereinbefore explained. In Fig. 1 four drops are shown tilted forward in 75 this position.

F is a key for transmitting signals, which is pivoted at f to the metallic frame a'', and is normally held by the pressure of an insulated spiral spring, f', against an insulated contact-point, g, which is termed its "resting contact." When the key is depressed, its contact with the point g is broken and a new one formed with another insulated contact-point, h, beneath it, which is termed the "working- 85 contact."

J is a peculiar form of circuit-changer called a "spring-jack," which consists of a metallic bar, j, pivoted at j' to an insulated support, while its free end rests in a seat, j'', formed of 90 insulating material. A contact-spring, j'', is attached to the under surface of the bar j, and this normally rests against a similar contact-spring, j'', attached to and in electrical connection with the frame a''. At the rear of the 95 metallic frame is attached a plate of insulating material, G, upon which are mounted four binding-screws. In Figs. 4 and 5 these are respectively numbered 1, 2, 3, and 4. The connecting-wires from these binding-screws 100 are run as follows: (Refer to Figs. 2 and 5.) No. 1 is connected by wire w' with the spring-jack j; No. 2 by the wire w'' with the working-contact h; No. 3 by the wire w''' with the resting-contact point g, passing through the 105 coils of the electro-magnet D; No. 4 by the wire w'' with an insulated spring, H, which, when required, is employed to establish a connection with an audible signal or electric bell, I, common to all the lines, which may be 110 mounted upon the case containing the switch, as shown in Fig. 1, or may be placed in any other convenient locality. This bell or alarm 115 is not in all cases an essential portion of the apparatus, as the sound caused by the falling of the annunciator-drop will usually be sufficient to notify the operator or attendant that a signal has been transmitted from one of the sub-stations. Each line entering the central station is attached to the binding-screw No. 1 120

in its appropriate compartment. The binding-screw No. 2 of each compartment is united to a wire leading to one pole of a battery common to all the lines, the other pole of which is to earth. Binding-screw No. 3 of each compartment is attached to a wire leading directly to the earth, while to binding-screw No. 4 is connected a local battery or branch of the main battery for operating the special audible signal hereinbefore referred to.

The normal circuit of each main line may be traced through its corresponding annunciator-compartment in the switch-board as follows: Entering at the binding-screw 1, it passes to

the spring-jack J, and thence through the contacts j^3 and j^4 to the frame $a'a^2$, thence through the key F to the contact-point g, through the coils of the electro-magnet D to binding-screw 5 No. 3, and thence to the earth.

I will now proceed to describe the device for establishing communication at the switch between two independent sub-station lines.

The operator's table C (seen in Fig. 1) is 10 provided with a number of switch cords or connectors. Each connector is made up of two lengths of flexible conducting-cord united by intervening stationary conductors, as seen at L and L' in Figs. 1 and 7. The arrangement will be best understood by reference to 15 Fig. 7, which exhibits a section of a portion of the operator's table, together with a theoretical diagram of the electrical connections.

S and S' are two metallic thimbles, which are 20 inserted in suitable apertures passing through the top of the table C, with their upper edges projecting a little above its surface.

The cords L and L' each consist of a flexible metallic conductor, which is provided with 25 a non-conducting covering braided or woven upon it. One end of the cord L is attached by means of a screw, p, to the switch-pin P, which is a wedge of metal of the form shown in Fig. 2^a, which is preferably provided with 30 an insulating-handle, whereby it may be conveniently manipulated. The switch-pin P normally rests upon the metallic thimble S, and the conducting-cord L, connected therewith, passes down through an opening within the 35 thimble, its opposite end being attached beneath the table at n' to one of the arms of the double-circuit changer N. The flexible conductor L is made long enough to hang in a loop, and a weight, M, is hung upon the bight 40 of the conductor, as shown in Figs. 1 and 7, thus tending to keep the switch-pin P in firm contact with the metallic thimble S. The other flexible conductor, L', in like manner passes through the thimble S', and is attached in precisely the same manner to the other switch-pin P' by means of a screw, p'. This conductor also carries a weight, M', and is attached at its opposite extremity to the other arm of the circuit-changer N. The two arms 45 of the circuit-changer N are linked together by an insulating connecting-bar, n, which may be provided with a pin or handle for convenience of manipulation. When this circuit-changer is in its normal position, its respective 50 arms rest upon two metallic studs, o o, which are united beneath the table by a conducting-wire, W', as indicated by the dotted line in Fig. 7. When in this position a continuous 55 electrical connection exists between the two switch-pins, P and P', by means of the cords L and L' and the circuit-changer N. When the circuit-changer N is shifted to the right, its arms are removed from o o and placed upon similar studs, t t. The last-named studs 60 are connected by wires w⁸ and w⁹ with the terminals of a telephone, T, which may be used either for transmitting or receiving oral com-

munications; or a separate transmitter and receiving-telephone may be employed, if preferred. The thimbles S and S' are connected 70 with each other and with the earth at X by means of wires w⁵ w⁶.

As hereinbefore stated, there is a number of independent connecting conducting-cords upon each operator's table, each one of them 75 being arranged in the manner just described. In Fig. 1 I have shown six of these conducting-cords, each provided with its own circuit-changer N, switch-pins P and P', cords L and L', and weights M and M'. The telephone T 80 is, however, common to all the conductors. Its respective terminal wires w⁸ and w⁹ are united with the corresponding studs throughout the series of six circuit-changers, N N, so that when any one of them is turned to the 85 right the telephone will be switched into the particular connecting-circuit to which that circuit-changer appertains. The several thimbles S S S' S', hereinbefore referred to, are 90 all likewise in electrical connection with each other and with the earth, as shown in Fig. 7.

The diagram, Fig. 6, illustrates the manner in which different switch-boards in the same office or in different offices are connected with 95 each other by the trunk lines. I prefer to reserve the upper row of compartments in each switch-board for the trunk and connecting lines, the remaining two rows being devoted to individual subscribers' lines. In Fig. 6 I have shown two central stations, each having 100 two switch-boards and one central station with a single switch-board. The four binding-screws in each compartment of each switch-board are arranged in the manner hereinbefore described. The several line-wires entering the station are each connected to the binding-screw No. 1 of their respective compartments. The trunk or connecting lines are in like manner so arranged as to unite the binding-screw No. 1 in the proper compartment 110 of one switch-board with the binding-screw No. 1 of a corresponding compartment of the other switch-board, as will be clearly understood by reference to Fig. 6. The number of trunk or connecting lines between different 115 switch-boards will of course be determined by the extent of intercommunication which is found to be required between subscribers' connected with different boards. The trunk-lines connecting different central offices are 120 arranged upon the same general plan as those connecting different switch-boards in the same office, with the exception that in large exchanges it will be more convenient to devote one or more entire switch-boards to the trunk-line connections and place that in charge of 125 a special operator. In small exchanges a part of one of the ordinary switch-boards, as illustrated in Fig. 1, will be sufficient to accommodate all the trunk-line connections required. 130

In order to illustrate the practical operation of my improved system, I will first describe the process of establishing communication between two sub-stations connected with the

same switch-board, and afterward between two sub-stations connected with different switch-boards. For example, if sub-station No. 15 wishes to communicate with sub-station No. 49, he first transmits a call-signal by means of his battery, magneto-generator, or other equivalent device, which signal passes through compartment No. 15 and releases the drop of the annunciator, allowing it to fall forward, as shown in Fig. 1. The operator at the table C inserts one of the switch-pins into the spring-jack of compartment No. 15, as shown, and then moves the corresponding circuit-changer N to the right, which brings the telephone T into the circuit. The circuit of line No. 15 now passes from the line-wire to the spring-jack, thence through the connecting-cord to the telephone, and from the telephone, through the other portion of the connecting-cord, to the other switch-pin, which rests upon one of the metallic thimbles, and is therefore in connection with the earth. The operator or attendant, by making use of the telephone T, ascertains that No. 15 wishes to communicate with No. 49; he accordingly removes the second switch-pin of the pair from the thimble on which it rests, thus breaking connection with the earth, and inserts it in spring-jack No. 49, still keeping his telephone in the connecting circuit until he learns that the correspondents are in communication with each other. He then turns his circuit-changer N to the left, thus removing the central-office telephone from the circuit and leaving the two lines in direct connection with each other through the circuit-changer N and flexible conductors L and L', as shown in Fig. 1. If the connection is to be made between two sub-stations which are connected with different switch-boards—for example, between No. 31 and a sub-station on switch-board No. 2—the operation is the same as that last described up to the point of inserting the second switch-pin, before doing which the operator at switch-board No. 1 first presses the key F in that compartment of his switch-board which communicates through one of the connecting-wires with switch-board No. 2. This completes a circuit from the signaling battery or generator R (see Fig. 5) through the binding screw 2 and the key F, thence through the frame and spring-jack j to the binding screw 1, from whence it traverses wire w⁶ to the annunciator No. 1 of board No. 2. The signaling-current operates this annunciator and passes to the ground in precisely the same manner as a signal received from an individual subscriber. After signaling the operator of the second switch-board in this manner, the operator of the first switch-board places the second switch-pin in the spring-jack of the compartment through which he signaled the second switch-board, and by his telephone, which is now looped between the line from whence the call proceeded and the extension of the same between the switch-boards, informs the operator thereof of the designating name or number of the sub-sta-

tion required, whereupon the latter assumes charge of the connection and completes the connection with the required sub-station precisely as in the first instance. The operation is similar when the subscriber desired is connected with a different central office. In this case connection is made with the trunk-line switch-board or compartment, and through this to the required central office, and at that office with the required subscriber. After completing a connection through his own switch-board, each operator restores the annunciator-drop to its normal position, and leaves the charge of the united circuit in the hands of the operator making the last connection. This operator, upon learning that the correspondence has terminated, transmits a call-signal by depressing the proper signal-key, which traverses the connecting or trunk line to the first switch-board. This action releases all the annunciator-drops of the compartments through which the connection has been made, thus notifying the several operators to restore all the connections to their normal position. When, for any reason, the constant attention of an operator is not required at the switch-board, a single battery or other electric generator may be connected with the binding-screws No. 4 of each compartment, which may be made to sound an electric alarm-bell whenever any one of the annunciator-drops falls forward and closes the circuit through its contact-point and spring. 100

I claim as my invention—

1. In a telephone central-office system in which the incoming lines are connected in groups with a series of sectional switch-boards, the combination, with the said sectional switch-boards, of a series of connecting-conductors extending between the switch-boards, and provided at each terminal with devices for transmitting and receiving signals, and with connecting devices whereby call-signals or communications may be electrically exchanged between any two switch-boards or between sub-stations connected by main lines with any two switch-boards. 105

2. The combination, substantially as herein-before described, of a series of sectional switch-boards, a series of main lines divided into groups between the said switch-boards, a series of independent connecting-conductors extending between each switch-board and every other switch-board, each of the said conductors being provided at each terminal thereof with signaling devices and circuit-connections, and a series of local connectors at each switch-board, each provided with a circuit-changer, 110 whereby a telephone common to the series may be connected in circuit with any one of the series, whereby each switch-board is enabled to signal and communicate with every other switch-board, and whereby a line terminating 115 at one switch-board may be interconnected with a line terminating at another switch-board, for the purposes specified. 120

3. The combination, substantially as here-

inbefore set forth, of a visual signal, an electro-magnet for causing the same to be actuated or exhibited, a key provided with a resting and a working contact, a spring-jack having 5 one of its terminals connected directly to a line-wire and its other terminal to the lever of said key, a connection from the resting-contact of said key to the earth, which includes said electro-magnet, and a connection 10 from the working-contact of said key to one pole of an electric generator whose remaining pole is connected to the earth.

4. The improved spring-jack, constructed substantially as hereinbefore set forth, consisting 15 of a yielding metallic bar which normally rests in a non-conducting seat, a contact-point which forms an electrical connection with said bar while it rests in said seat, and a tapering metallic switch-pin which, when inserted between 20 the yielding bar and its non-conducting seat, forms an electrical connection with the said bar, and at the same time lifts it from the contact-point.

5. The combination, substantially as hereinbefore set forth, of a non-conducting base, 25 a metallic thimble inserted in said base and electrically connected with the earth, a flexible conductor provided with a non-conducting envelope passing through said thimble, a metallic switch-pin or connector attached to and 30 forming one terminal of said flexible conductor, and a weight attached to or acting upon said flexible conductor, tending to keep said terminal normally in electrical contact with said metallic thimble.

6. The combination, substantially as hereinbefore set forth, of a metallic thimble electrically connected with the earth, a flexible 35

conductor provided with a non-conducting envelope passing through said thimble, a metallic switch-pin or connector attached to and forming one terminal of said flexible conductor, and a weight attached to or acting upon said flexible conductor, tending to keep said terminal normally in electrical contact with said metallic thimble. 40

7. The combination, substantially as hereinbefore set forth, of two metallic thimbles electrically connected with each other and with the earth, two flexible conductors with non-conducting envelopes, said conductors passing through said thimbles, respectively, metallic switch-pins or connectors forming one terminal of each of said flexible conductors, a telephone, and a circuit-changer for connecting the remaining terminals of said flexible conductors together, either directly or through 50 said telephone.

8. The combination, substantially as hereinbefore set forth, of a metallic thimble, a flexible conductor provided with a non-conducting envelope passing through said thimble, and a metallic switch-pin or connector attached to and forming one terminal of said flexible conductor, which terminal is larger than the opening of the thimble, whereby the terminal is prevented from being drawn 65 through the thimble by the tension of the conductor.

In testimony whereof I have hereunto subscribed my name this 14th day of September, A. D. 1881.

THOMAS B. DOOLITTLE.
